MICA CIGARETTE WINDING MACHINE

Hartwell W. Webb, Flint, Mich., assignor to General Motors Corporation, Detroit, Mich., a corporation of Delaware

Application August 29, 1936, Serial No. 98,557

6 Claims. (Cl. 242—75)

The winding of mica cigarettes on the electrodes of mica insulated spark plugs has been a costly manual operation. It required the services of a highly skilled worker and even then was slow and tedious. At best, it was very wasteful of material because the strips of mica employed were frequently broken or scratched or rendered unserviceable by films of oil from the hands of the worker.

10 This invention has to do with a machine by which mica cigarettes may be wound on the electrodes of mica insulated spark plugs cheaply, quickly and easily and with very little waste of material even by a worker who has had very little training.

For a detailed disclosure of such a machine, reference is made to the accompanying drawings and the following specification where it is shown and described.

20 In the accompanying drawings:

Figure 1 is a top plan view of a machine in accordance with my invention with a spark plug electrode in place in it;

Figure 2 is a fragmentary front elevation of 25 the machine;

Figure 3 is an end elevation of the machine with parts broken away and in section and in different positions than those in which they are shown in Figure 1;

30 Figure 4 is an enlarged fragmentary view of the roller chain which is incorporated in the machine;

Figure 5 is an enlarged view, mainly in section, of a portion of the machine with the parts in 35 the positions in which they are shown in Figure 3;

Figure 6 shows a spark plug electrode with a mica cigarette wound on it.

The basis of the machine shown in the drawings is a small lathe which consists of a bed 10 on which there are mounted a headstock 11 and a tailstock 12. In the headstock, there is journaled a spindle 13 on which there are secured a series of driving pulleys 14. In the tailstock, 45 there is journaled a spindle 15 which may be moved back and forth lengthwise and held in any desired position by a lock operated by a handle 16. The spindle 13 carries a chuck 17 which may be opened and closed by a knob 18.

50 Into the inner end of the spindle 16, there extends a bore 19 which is designed to accommodate one end of a spark plug electrode.

In a depression in the bed 10 between the headstock 11 and the tailstock 12 there is mounted a crosspiece 20. In the upper surface of the

crosspiece on one side of the axis of the spindles 13 and 15, there are formed ways which extend at a right angle to the axis of the spindles. In the ways, there is mounted so that it may slide lengthwise thereof a plate 21 whose upper surface 5 is preferably chromium plated and polished.

To the inner end of the plate 21, there is connected a roller chain 22 which is approximately equal in width to the plate. The chain consists of three sets of elongated links 23 with a triangular link 24 at one end of each set separated from each other crosswise of the chain. The elongated links of the several sets are connected in series one to another by pintles 25 which extend the full width of the chain and through 10 their overlapping ends. The triangular links are connected to the outer ends of the elongated links at one end of the sets by another pintle 25 which extends through the latter and through

15 the former near one of their apices. The triangular links are also connected to each other by pins 26 similar to the pintles 25 which extend through them near their other apices. The outer ends of the elongated links at the other 20 end of the sets extend into notches 27 in the inner end of the plate 21 and are connected thereto by a pintle 28 which extends through them and the inner end of the plate. On each of the pintles 25 and pins 26, there are sleeved 25 so that they may rotate on the pintles and pins 30 four rollers 29 which are preferably chromium plated and polished. One of these rollers is disposed between the intermediate and each of the outer sets of links and one is disposed on the outer side of each of the outer sets of links. The 35 several elements of the chain are maintained in assembled relation by cylindrical nuts 30 threaded on the pintles 25 and pins 26 and disposed in counterbores in the outer ends of the outer rollers 29.

To hold the chain 22 wrapped around a spark plug electrode disposed between the spindles 13 and 15, as shown in Figures 3 and 5, there are provided hooks 31 which may engage over extensions 32 of the pin 26 which is outermost when 40 the chain is wrapped around the electrode. Each of the hooks 31 is secured to one end of a shaft 33 which extends through and is journaled in the crosspiece 20. The hooks 31 are urged to the

positions in which they engage over the extensions 32 by a spring 34 which is disposed within 45 a bore in the crosspiece 20 and engages a flat on the shaft 33 through the intermediary of a plunger 35 but may be moved to free the outer 50 end of the chain so that it may be unwrapped 55

from the electrode by depressing one of the fingers 36 which are formed as angularly disposed extensions of the hooks 31. One of the hooks 31 is disposed in a shallow recess 43 in the side of the crosspiece 20 and movement of the hooks in the direction in which they are urged by the spring 34 is limited by engagement of this hook with a wall of the recess.

So that the chain 22 will snugly embrace the spark plug electrode disposed between the spindles 13 and 15 and may accommodate itself to the increase in the diameter of the work as the operation of winding the mica cigarette on the electrode proceeds, there is provided a spring 37 which is disposed in a bore in the arm of the crosspiece 20 on which the plate 21 is mounted and tends to move the plate away from the axis of the spindles 13 and 15 through the intermediaries of a plunger 38 and a setscrew 39 which extends through a lug 40 secured to the lower side of the plate.

On the arm of the crosspiece 20 which is disposed on the opposite side of the axis of the spindles 13 and 15 from that on which the plate 21 is mounted, there is mounted an indicator 41. The indicator 41 is so mounted that it may be moved from the inoperative position in which it is shown in Figure 1 to the position in which it is shown in Figure 3 in which its feeler 42 engages one of the rollers 29 of the chain 22 and it indicates the thickness of the mica cigarette which has been wound on the spark plug electrode disposed between the spindles 13 and 15.

In using the machine shown in the drawings and hereinbefore described, the operator places an electrode *a* on which a mica cigarette *b* is to be wound in the machine with one end secured in the chuck 17 and the other inserted in the bore 19 in the spindle 15. Then the operator slides the plate 21 toward the axis of the spindles 13 and 15 and wraps the chain 22 around the electrode and engages the extensions 32 under the hooks 31 as shown in Figures 3 and 5. After these things have been done, the operator places a strip *c* of mica on the plate 21 and slides it toward the axis of the spindles 13 and 15 until its inner end is engaged between the lower side of the electrode *a* and the chain 22. Then, by turning the pulley assembly 14, the operator rotates the electrode *a* in a clockwise direction when viewed as shown in Figures 3 and 5. This rotation of the electrode, as Figure 5 indicates, causes the strip of mica *c* to be wound around the electrode. After all except the end of the strip of mica has been wound around the electrode, the operator slides another strip along the plate 21 until its inner end is engaged between the unwound end of the first strip and the portion thereof that has been wound on the electrode and again rotates the electrode to wind the second strip around it and the first. Additional strips are similarly wound around the electrode and the strips previously wound on it until a test by the indicator 41 shows that the cigarette *b* is of the desired thickness. Then the hooks 31 are disengaged from the extensions 32, the chain 22 unwrapped from around the electrode and the cigarette and the electrode with the mica cigarette wound on it removed from the machine.

When the machine shown in the drawings and hereinbefore described is used very little handling of the mica strips *c* by the operator is necessary. Therefore, and because the only parts of the machine with which the strips contact (the plate 21 and the rollers 29) are smooth and

highly polished and the strips have rolling, not sliding, contact with the chain 22, wastage of mica strips as a result of breaking, cracking and soiling and rejects of spark plugs due to defects in the mica cigarettes are minimized. The operation of winding mica cigarettes is rendered much faster and less tedious by my machine. Moreover, mica cigarettes produced by my machine are much more uniform than those produced by hand because the tightness of the turns of the mica strips is automatically determined by the spring 37. All of these things contribute to the production of better spark plugs more cheaply when my machine is used than when the mica cigarettes are wound by hand.

I claim:

1. In a machine for winding material, a flexible member within which the material may be wound and a shelf over which the material may be advanced into the flexible member and to which one end of the latter is anchored, the shelf being adjustable lengthwise of the flexible member so that the latter may accommodate itself to the increase in diameter of the product as the winding operation proceeds.

2. In a machine for winding material, a flexible member within which the material may be wound, a shelf over which the material may be advanced into the flexible member and to which one end of the latter is anchored, the shelf being adjustable in the direction of the length of the flexible member so that the latter may accommodate itself to the increase in diameter of the product as the winding operation proceeds, and means for releasably anchoring the other end of the flexible member so that it may be unwrapped from around the product.

3. In a machine for winding material, a flexible member which is anchored at one end and within which the material may be wound, a shelf over which the material may be advanced into the flexible member and to which the other end of the flexible member is anchored, the shelf being adjustable in the direction of the length of the flexible member, and means for resiliently urging the shelf in the direction to wrap the flexible member more tightly around the wound material.

4. In a machine for winding strip mica on a spark plug electrode, means for supporting a spark plug electrode so that it may be rotated, a shelf over which strip mica may be advanced toward the spark plug electrode movable toward and away from the axis thereof, a roller chain which may be wrapped around the spark plug electrode anchored at one end to the end of the shelf nearest the spark plug electrode, means for releasably anchoring the other end of the chain when it is wrapped around the spark plug electrode, and means for yieldingly urging the shelf away from the spark plug electrode so that the chain will snugly embrace it.

5. In a machine for winding material on a mandrel-like member, means by which the mandrel-like member may be supported and rotated, a roller chain within which the material may be wound on the mandrel-like member anchored at one end, a triangular link with rollers journaled near two of its apices at the other end of the chain, and means which engages the triangular link near the other of the apices to hold the rollers which are journaled therein against the material wound on the mandrel-like member.

6. That improvement in the art of manufacturing mica insulated spark plugs which consists of

a machine for winding strip mica on a spark plug electrode which includes: means for mounting a spark plug electrode so that it can be rotated including a chuck for gripping one end and a spindle for supporting the other end of the electrode, a roller chain which may be wrapped around the electrode for holding the strip mica wound on it around the electrode, means including a resilient member for anchoring one end of

the chain so that it will snugly embrace the strip mica wound on the electrode and yet accommodate itself to the increase in the diameter of the product which occurs during the winding operation, and means including a releasable catch for anchoring the other end of the chain so that it may be unwrapped from around the product when the winding operation is completed. 5
